CLAIM

We claim the ornamental design for a heating ventilation and air conditioning controller, as shown and described.

DESCRIPTION

FIG. 1 is a front right perspective view of the claimed heating ventilation and air conditioning controller;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The ornamental design which is claimed is shown in solid lines in the drawings. Broken lines of equal or substantially equal length dashes in the figures are for illustrative purposes only and form no part of the claimed design. Broken lines formed of unequal length dashes (i.e., dash-dot) show boundaries between claimed and unclaimed portions of the design. Oblique lines show a transparent, translucent, highly polished, or reflective surface, and not surface ornamentation.
